UNITED STATES PATENT OFFICE.

RASMUS JENSEN, OF LOS ANGELES, CALIFORNIA.

WATER-VAPORIZER FOR CARBURETERS.

1,163,930.

Specification of Letters Patent. Patented Dec. 14, 1915.

Application filed October 10, 1914. Serial No. 866,052.

To all whom it may concern:

Be it known that I, RASMUS JENSEN, a citizen of the United States, residing at Los Angeles, in the county of Los Angeles and State of California, have invented a new and useful Water-Vaporizer for Carbureters, of which the following is a specification.

The primary object of this invention is to provide an automatic water vaporizer for carbureters which will supply a proper mixture of air and water to the mixing chamber of the carbureter, and which automatically varies the relative proportions of air and moisture as the speed of the engine requires to operate most efficiently.

Another object of the invention is to provide a water vaporizer of this nature having a thermostatically controlled water regulating valve.

Another, and no less important, object of the invention is to provide in a carbureter water vaporizer a gravity air valve which operates to open a water inlet valve in such wise that the amount of water obtained is directly proportional to the amount of air.

With these and other objects in view, the invention consists in certain novel features of construction, combination and arrangement of parts as will be hereinafter fully described, illustrated and claimed.

The drawing is a longitudinal sectional view partly in elevation through the preferred embodiment of my water vaporizer.

Referring in detail to the drawing by numbers, 1 designates as an entirety the body casting which, as shown, is preferably formed with a hollow interior providing a mixing chamber 2 and an outlet passage 3, the exterior wall of which is formed with a pipe thread 4 to make a screw connection with the mixing chamber of a carbureter, not shown.

An opening 5 is formed in the bottom of the casting communicant with the mixing chamber 2 and in this opening is threadedly secured valve cage 6, having ports 7 and a central sleeve 8, which slidably receives the stem 9 of a suction operated air valve 10. The upper portion 11 of the valve 10 is of frusto-conical formation, and the lower portion 12 is beveled downwardly and inwardly to form an inverted frusto-conical conformation. The beveled portion 12 seats against the corresponding beveled face 13 of the valve cage.

Directly above the center of the valve 10,

the body casting 1 is formed with a port 14 opening into a chamber 15 formed by an internally threaded boss or sleeve 16. The port 13 is of less diameter than the interior of the sleeve 16, and so a seat for the valve 17 is provided. This valve has an inverted frusto-conical head which carries an upwardly projecting stem 18, which projects into a bore 19 formed in an adjusting screw 20. The adjusting screw threads into the chamber 15 and bears against one end of the helical spring 21, the other end of said spring resting upon the top of the valve 17.

A rearwardly extending passage 22 connects at its inner end with the lower portion of the chamber 15, and receives a needle valve 23 which controls the flow of water through the inner end portion or bypass 24 of the passage 22.

An inclined nipple 24' having a bore 25 connecting with the passage 22 is provided for connection to a water source.

The valve 23 is thermostatically operated by the thermostat 26 preferably formed of a steel strip 27 and a copper strip 28. The thermostat is bent into the form of an open loop, one end of which is connected to the casing by a screw 29, and the other end of which is formed with a threaded opening 30 through which extends the valve 23, said valve being threaded for a portion of its length to engage the threads of the opening in the thermostat. 28 indicates a nipple opening in the top of the mixing chamber 2 and being designed for connection with a moist air supply such as the radiator of an engine.

When starting a motor cold, the thermostat 27 is contracted, and the valve 23 seated so that no water may flow through the bypass 24 into the chamber 15. When the motor speeds up the air intake valve 10 is raised from its seat a distance directly proportional to the speed of the engine, thus admitting air through ports 7 into the mixing chamber 2. After the valve 10 has raised but a slight distance, it engages the valve 17, lifting the latter upwardly and opening the port 23, so that communication between the mixing chamber 2 and bypass 24 is established. As soon as the motor warms up, the heat radiated affects the thermostat 26, causing it to expand and unseat the needle valve 23, the degree of movement of the valve being directly proportional to the heat radiated. This heat is proportional

to the speed of the engine. When the valve 23 is unseated, water flows into the chamber 15 and then into the mixing chamber 2 onto the top portion of the valve 10. The 5 inrushing air coming through the ports 9 strikes the water tearing it from the surface of the valve and thoroughly atomizing it. The faster the engine is run, the wider the valves 10 and 23 will open, and the more 10 heat will be generated, causing the thermostat to expand greatly and admit sufficient water to keep the engine from overheating under heavy working strain. When the engine is running slow with a light load, valves 15 10 and 23 remain closed through the force of gravity and the tension of the spring 21 respectively, and no moist air is supplied through the nipple 28 which latter is always in open communication with the interior 20 of the casting.

From the foregoing description, taken in connection with the accompanying drawings, it will be apparent that I have provided a very simple and practical water 25 vaporizer for carburetors, which operates automatically, as the speed of the engine varies so that the proper amount of moisture is always supplied to secure the greatest efficiency and to prevent the cylinders 30 overheating under heavy load.

What I claim is:

1. In combination, a body designed to be connected to the intake of an explosive engine and having an air outlet passage and an air inlet port, a valve between said passage and port, a fluid supply port communicating with the passage, and a valve for the fluid supply port operated to open by movement of the air admission valve.
2. In combination, a body designed to be

connected to the intake of an explosive engine and having an air outlet passage and an air inlet port, a valve operated to open by suction of the engine, a fluid supply port communicating with the passage, and a 45 valve for the fluid supply port operated to open by opening of the air admission valve.

3. In combination, a body designed to be connected to the intake of an explosive engine and having an air outlet passage and 50 an air inlet port, a valve between said passage and port, a fluid supply port communicating with the passage, a second valve to control said fluid supply port, and a thermostat mounted on the body and connected 55 to the second valve to automatically regulate the degree of opening of the said second valve.

4. In combination, a body designed to be connected to the intake of an explosive engine and having an air outlet passage and an air inlet port, a valve between said passage and port, a fluid supply port communicating with said passage, a second valve 60 for the fluid supply port operated to open by movement of the air admission valve, a by-pass communicating with the fluid supply port, a third valve for said by-pass, and a thermostat mounted on the body and connected to the third valve to automatically 65 regulate the degree of opening of said third valve.

In testimony whereof, I have hereunto set my hand at Los Angeles, California, this 2nd day of October 1914.

RASMUS JENSEN.
